UNITED STATES PATENT OFFICE

WILLIAM D. ROSE, OF PORTLAND, OREGON

DESIGN FOR A MAGAZINE COVER

Application filed June 24, 1930. Serial No. 36,159. Term of patent 3½ years.

To all whom it may concern:

Be it known that I, WILLIAM D. ROSE, a citizen of the United States, residing at Portland, in the county of Multnomah and State of Oregon, have invented a new, original, and ornamental Design for a Magazine Cover, of which the following is a specification, reference being had to the accompanying drawing, forming part thereof, and in which the figure is a face view of the cover of a magazine, showing my new design, the opposite side of the cover being without the design.

I claim:

The ornamental design for a magazine cover, as shown and described.

WILLIAM D. ROSE.
